ARCHERY BOW AND SIGHT THEREFOR

John R. Tate, Whittier, Calif.

Application October 15, 1937, Serial No. 169,326

7 Claims. (Cl. 124—23)

This invention relates to certain improvements in archery bows and sights therefor, and the nature and objects of the invention will be readily recognized and understood by those skilled in the art to which the invention pertains, in the light of the following explanation and detailed description of the accompanying drawings illustrating what I now consider to be the preferred embodiments or mechanical expressions of my invention from among various other forms, designs, arrangements, constructions and combinations of which the invention is capable within the broad spirit and scope thereof.

Archery bows generally are of a length of the order of approximately six (6) feet, at least, so that they are rather unwieldy and cumbersome for transportation and/or storage. Various designs and constructions of such bows have been suggested to enable their being disassembled or knocked-down into sections for carriage or storage purposes, but generally such suggested designs involve complex constructions with increased number of parts and elements making up a bow, so that not only is the cost of the bow increased but the efficiency and accuracy may be decreased.

It is a general object of my present invention to provide a design and construction of archery bow which may be readily disassembled or knocked down for carriage or storage purposes, but which is of extremely simple construction to embody merely a handle and upper and lower limbs detachably received by the bow handle without the use of any fastening means, such as screws, clamps or the like, and with the bow limbs maintained in assembled relation with the bow handle merely by the bow string in operative position placing the limbs under tension, and the limbs releasable for disassembly and removal from the handle by detaching the bow string from operative engagement with one of the bow limbs.

A feature and characteristic of the invention in carrying out the foregoing general object resides in the design of the bow handle to provide opposite end bow limb receiving sockets and in the construction of the inner ends of the bow limbs to fit into the handle sockets in such a manner that, as the bow string is drawn back by the archer to release an arrow, the ends of the limbs are tightened in the handle sockets.

Another object of my invention is to provide an improved design of sight for an archery bow, which is readily adjustable universally, that is, vertically and laterally, as required to meet the needs of a particular archer and the requirements

of the particular conditions under which a bow is being used.

A further object of the invention is to provide an efficient design of mounting for the sight on a bow of the foregoing type, by which the sight is adapted to be maintained in operative position on the bow by securing the sight mounting in the upper end socket of the bow handle between the handle and the end of the upper limb of the bow received in such socket, the sight being detachable and removable when the bow is disassembled.

Another main object of my invention is to provide a design, construction and arrangement of knock-down or sectional bow of the above referred to character, which is extremely simple mechanically and structurally and embodies a minimum of parts and elements capable of ready manufacture at relatively low cost, yet which provides an efficient and accurate bow in use; and further which enables the bow limbs being constructed of such wood materials as have been established as preferred and most efficient for archery bow purposes.

With the foregoing general objects in view, as well as certain others which will be evident from the following description, my invention consists in certain novel features in design and in combination and construction of parts and elements, all as will be more fully and particularly referred to and specified hereinafter.

Referring to the accompanying drawings, in which similar reference characters refer to corresponding parts throughout the several figures thereof:

Fig. 1 is a view in side elevation of an archery bow and sight embodying the invention, in assembled and operative position.

Fig. 2 is an enlarged perspective view of the bow handle and inner ends of the upper and lower bow limbs together with the bow sight, when separated and disassembled but in their relative positions for assembly.

Fig. 3 is an enlarged view in side elevation of the bow handle with the upper and lower limbs of the bow in assembled position in the handle sockets and the sight in mounted position, the inner end portions only of the bow limbs being shown.

Fig. 4 is a view in rear elevation of the assembled bow handle, limbs and sight of Fig. 3.

Fig. 5 is a view in vertical longitudinal section through the bow handle of Figs. 3 and 4, the ends of the bow limbs and the bow sight mounted in the handle being shown in side elevation.

Fig. 6 is a horizontal, transverse section

through the bow handle and upper bow limb mounted therein, taken as on the line 6—6 of Fig. 3, and showing the sight mounting plate in assembled position in the handle socket.

5 Fig. 7 is a view in rear elevation of the inner end of the lower limb of the bow showing the wedge block or member thereon for cooperation with the bow handle socket.

One possible embodiment of an archery bow incorporating the several features of the invention is illustrated by way of an example in the accompanying drawings, and essentially includes, referring particularly to Fig. 1, the bow handle 10, upper limb 20, lower limb 30, and the bow string 40. In accordance with the invention, the upper and lower limbs 20 and 30 are removably maintained in the opposite ends, respectively, of the bow handle 10 by the bow string 40 connected to and between the bow limbs in operative position drawing or bending the limbs rearwardly to initially place the limbs under tension for use of the bow. Due to the design and construction of the bow handle and the inner ends of the bow limbs, the latter are held and maintained in their operative, assembled position by the bow string in its above referred to operative position as shown in Fig. 1, and are released for removal by unstringing the bow, all without the use of any fastening or other means for securing or clamping the bow limbs into the bow handle.

In the present instance, I have selected a design and construction for the bow handle 10, by which the handle is formed of a tubular metal element, such as a casting or the like of a light-weight metal as aluminum, or one of the metal alloys as duralumin, although my invention is not limited to any particular material for the bow handle forming element. This handle forming element is slightly bent or curved rearwardly from its central portion toward its opposite ends, that is, is of slight arcuate form, and preferably is provided with the end beads or rounded guard shoulders 10a extended at least around the side and rear of each end of the handle member.

Along one side of the handle element, in this instance, the left side, a longitudinally extended raised portion 10b is provided intermediate the opposite end beads 10a, to form a surface against which an arrow to be cast by the bow is held and across which the arrow slides in drawing the bow and releasing the arrow. If desired, such an arrow engaged surface 10b may be provided on the right side of handle 10, or such surfaces may be formed at both sides thereof. In order to provide an efficient hand grip surface, the element forming the handle 10 is covered with a suitable material, such as leather, rawhide or the like 10c (see Fig. 5) between the end beads or shoulders 10a, and with the outer surface substantially flush with or in a plane slightly below the plane of the outer surface of the raised, arrow engaging portion 10b of the handle forming element.

The bore or passage 11 (see Fig. 5) through the tubular handle forming element may be, as in the example hereof, of generally rectangular cross section, that is non-circular but having rounded or curved corner portions. This bore 11 from its intermediate or central portion within the element, increases in width or cross sectional area outwardly to the opposite ends of the handle to form the upper end and lower end bow limb receiving sockets 12 and 14, respectively.

The upper end socket 12 of handle 10 has its rear wall 12a curved or inclined upwardly and

rearwardly from its inner end (see Fig. 5) and is transversely curved so as to be substantially concave in section, as will be clear from Fig. 6. The forward wall 12b of this upper socket is substantially straight and presents a flat surface with a vertical groove or slot 12c formed extending longitudinally thereof, which slot opens through the upper edge wall of the handle forming element and also has in the example hereof, its opposite side edges undercut as shown by Fig. 6.

10 The lower end socket 14 of the bow handle has the rear wall 14a thereof curved or inclined outwardly and rearwardly (see Fig. 5) and is transversely curved so that such wall is substantially concave in cross section, in a manner similar to 15 upper socket rear wall 12a as shown by Fig. 6. The forward wall 14b of this lower bow limb socket is substantially straight and presents an approximately flat surface, as will be clear by reference to Fig. 1 in connection with the showing in Fig. 6 of the similar forward wall 12b of the upper socket 12 of the bow handle 10.

20 The upper and lower bow handle sockets 12 and 14 are designed to removably receive and hold the inner ends of the upper and lower bow limbs 20 and 30 with such elements of the bow in 25 assembled position as shown by Figs. 1, 3, 4 and 5 of the accompanying drawings. Due to the design and construction of the bow handle sockets and the arrangement of the invention for 30 releasably holding the bow limbs therein, solely by forces exerted thereon by the bow string 40 in strung position, the bow limbs can be practically manufactured from any of the woods efficiently suitable for archery bow use, such for example, 35 as hickory, ash, lemon, yew and hedgewood.

The upper and lower bow limbs 20 and 30 are 40 substantially identical in design and construction, each being formed of a length of a suitable wood which is tapered or decreased in cross 45 sectional area outwardly and is preformed or shaped to curve outwardly and rearwardly from the inner end portion of the limb, as will be clear by reference to Fig. 1 of the drawings in particular. Each bow limb in the example hereof is formed with the substantially flat forward 50 side or surface 1, and terminates at its inner end in the root or handle socket fitting portion 2. Such root or socket fitting end portion 2 of a 55 bow limb is formed by reducing the width of the bow limb to provide the shoulders 2a at opposite side edges of the limb and then tapering such root or socket portion outwardly to the end thereof. Each tapered inner or root end 2 of a bow limb is shaped to fit into a socket 12 or 14 of the 60 bow handle 10, and is provided with the forward side substantially straight flat wall 2b (see Figs. 2 and 5) adapted to fit against the forward flat wall 12b or 14b of a handle socket 12 or 14, with the bow limb in mounted position in such handle 65 socket.

Following a further feature of the invention, each bow limb 20 and 30 is provided with means for cooperating with the rear wall of the handle socket 12 or 14 in which mounted, to cause a 70 wedging and tightening of the bow limbs in their respective handle sockets as the bow string 40 is drawn back for casting or propelling an arrow. Such a means in the present example, takes the form of a wedge block 3 secured in fixed position on the rear side of each bow limb root 2 adjacent the shoulders 2a of the limb. Each wedge block 3 decreases in thickness from its outer end inwardly along the limb root by sloping or inclining its outer side inwardly toward 75

the limb root. These wedge blocks are preferably formed of a hard wood, such, for example, as ebony wood, and are secured to the limb roots 2 in any suitable manner, as, for example, by means 5 of a suitable fastening element, such as a nail screw or the like 3a (see Fig. 5), with or without the use of glue or cement between the limb root and wedge block, as may be found expedient.

The archery bow of the invention is assembled 10 for use, referring now to Figs. 1 and 5 in particular, by freely inserting the root ends 2 of the upper and lower limbs 20 and 30 in the handle sockets 12 and 14, respectively, of the handle 10, with the flat front walls 2b of the limb roots 15 engaged against the flat forward walls 12b and 14b, respectively, of the handle sockets. In such inserted assembled position, the wedge blocks 3 of the upper and lower limb roots 2 fit within the sockets in engagement with the outer end 20 portions of the rearwardly and outwardly curved 25 rear walls 12a and 14a, respectively, of the said handle sockets, as clearly shown by Figs. 3 and 5 of the drawings. The bow string 40 is then connected into operative position between the outer 30 ends of the assembled upper and lower bow limbs 20 and 30 to initially bend or draw the limbs rearwardly into initially sprung position, in the usual manner of stringing an archery bow familiar in this art.

30 Thus, under the action of the bow string 40 when so connected between the bow limbs 20 and 30, the inner, root ends 2 of the limbs are firmly forced and held in the handle sockets 12 and 14 in assembled position to complete the bow 35 ready for use, as shown by Fig. 1. As a result of the design and relative arrangement of the wedge blocks 3 and their position in the handle sockets, each time the bow string 40 is drawn rearwardly into arrow casting or projecting position, these 40 hard wood blocks function as wedges acting against the curved rear socket walls 12a and 14a, to further tighten and force the limb roots 2 into the sockets and tightly and rigidly hold the limbs in fixed position during the drawing of and 45 arrow casting by the bow. Hence, such tight mounting and substantially rigid mounting of the bow limbs 20 and 30 in the bow handle 10 is accomplished solely by the forces acting on the limbs when the bow is strung for use, and entirely 50 without the employment of any separate or additional securing or clamping means.

When it is desired to disassemble the bow for transportation or storage, it is merely necessary to unstring the bow by detaching the bow 55 string 40 from one of the bow limbs, which instantly releases the tension on the limbs that holds them in their assembled position in the handle sockets, so that the bow limbs 20 and 30 can then be removed from the sockets 12 and 14 60 to separate them from the handle 10. Assuming a bow of substantially a six (6) foot length, the disassembled or knocked-down bow can then be transported or stored to occupy a space of a length of not over approximately a length of three 65 (3) feet.

The invention also includes a bow sight S and its mounting as a feature thereof, in combination and cooperation with the knockdown or sectional bow of my invention as hereinbefore described. 70 The sight S consists of tube or sighting member 50 of any suitable material, such, for example, as aluminum or other light-weight metal or alloy. This tube has the restricted sight opening forming forward end 50a and the rear enlarged bore 75 eye opening providing end 50b. The sighting tube

is adapted to be mounted on the mounting in generally horizontally disposed position but adjustable so as to have its bore lined between an eye of the archer and the target.

A mounting for the sighting tube 50 providing 5 for elevational and lateral or horizontal adjustment is provided, and in accordance with my invention such mounting is designed for cooperative combination with the upper bow limb 20 and the upper socket 12 of the bow handle 10. Such 10 a mounting may, as in the example hereof, embody a mounting base plate 51 of general wedge formation having a laterally extended arm 52 at its upper end which arm terminates in a vertically disposed column or standard 53. A bracket 15 54 is slidably mounted on column 53 for vertical adjustment as well as horizontal or rotary adjustment thereon. A set screw 54a is provided for securing bracket 54 in its adjusted positions on column 53. The sighting tube 50 is formed with 20 a depending arm 55 intermediate the length of the tube, which is rotatably mounted on the outer end of bracket 54 for vertical rocking or elevational adjustment thereon. A clamping screw 56 is provided for securing the arm 55 and its tube 50 in 25 adjusted position.

The sight S and its mounting are secured in position on the bow when the latter is assembled by inserting the base plate 51 downwardly in the undercut slot 12c formed in the forward wall 12b 30 of the upper limb slot 12 of the bow handle. The vertical column of the sight mounting is then disposed on the left side of the bow with the sighting tube 50 in generally horizontally disposed position spaced from the left side of the upper bow limb 20. 35 This arrangement and location is preferred for an archer who holds the bow in his left hand by handle 10 and draws the bow with his right hand, but if desired the sight can be arranged for mounting to locate tube 50 at the right side of the bow 40 to accommodate an archer holding the bow with his right hand and drawing the bow with his left hand.

In either mounting arrangement the mounting plate 51 in socket slot 12c is located so as not 45 to interfere with the insertion or removal of the upper bow limb 20 in socket 12, and the root end 2 of limb 20 when inserted and secured in the socket may bear against and wedge the plate 51 in position against displacement so as to maintain the mounting and sight carried thereby in the required operative position on the bow. Upon removal of the upper bow limb 20, the mounting plate 51 for sight S is released and the sight and its mounting may then be removed as a unit. 55

Due to the adjustments provided by the sight mounting, the sighting tube S can be raised or lowered on column 53, can be swung horizontally or laterally about column 53 as an axis, and can be rocked vertically for elevational angular adjustment about the bracket 54 as an axis. Thus, the sighting tube 50 can be positioned to meet the sighting requirements of the archer using the bow, both as to initial position relative to the eye of the archer and as to the sighting requirements 60 under the conditions of use of the bow as to target and windage.

By the design, construction and arrangement of the foregoing described embodiment exemplifying the several features of my invention, I have produced an archery bow of extreme simplicity structurally and a bow capable of ready manufacture at low cost of production, yet which is capable of being knocked-down or disassembled quickly into sections for transportation and storage. The bow 75

can be as readily assembled by simply placing the bow limbs in the handle sockets and then stringing the bow, without requiring any other fastening, clamping or securing members than provided by 5 the bow handle sockets, bow limbs and bow string in their cooperating relation in assembled positions. I have further provided a practical and efficient sight for an archery bow together with a mounting for positioning the sight on the bow, and 10 have designed and arranged the sight and its mounting for cooperative assembly with the bow handle and one of the separable bow limbs so that the sight and mounting can be assembled in combination with such elements of the bow but 15 by which the sight and its mounting can be assembled on or removed from the assembled bow without requiring disassembly or separation of the bow elements.

It is also evident that various changes, modifications, substitutions, additions and eliminations 20 may be resorted to without departing from the broad scope of my invention, and hence I do not desire to limit myself in all respects to the exact and specific disclosures hereof.

25 Desiring to protect my invention in the broadest manner legally possible, what I claim is:

1. The combination in an archery bow of a bow handle having bow limb receiving sockets, bow limbs removably inserted in said sockets, a 30 bow string connected between the limbs and maintaining the limbs in their sockets against displacement, and a bow sight unit having a mounting base removably mounted in one of said bow sockets and maintained against displacement 35 by the bow limb in such socket.

2. The combination in an archery bow including a bow string therefor, of separable bow handle and bow limbs, said handle and limbs being 40 releasably maintained in assembled relation by said bow string, and a bow sight unit mounted on said bow handle and maintained against displacement by one of said bow limbs.

3. In an archery bow, in combination, a bow handle having a bow limb receiving socket there- 45 in, a bow limb removably held in said socket, and a bow sight unit including a mounting for the unit, said mounting removably inserted in the bow limb socket and normally maintained against displacement by said bow limb in the 50 socket.

55 4. In an archery bow, in combination, a bow handle having a bow limb receiving socket therein, a bow limb removably inserted in said socket, said bow handle socket having a groove longitudinally disposed in a wall thereof, and a bow sight unit, including a mounting base plate therefor, said mounting base plate being removably received in said socket groove to position the sight unit in operative position on the bow 60 handle.

5. In an archery bow, in combination, a bow handle having a bow limb receiving socket therein, a bow limb having a root end formed to removably fit into said socket to position the bow limb on the said handle, a sight unit including 5 a wedge base plate adapted to be inserted in said socket between a wall of the socket the root end of the bow limb fitted into the socket, said base plate having a laterally extended arm terminating in a vertically disposed column positioned spaced to one side of the bow limb with the unit in mounted position, and a sight tube adjustably supported from said column.

6. The combination in an archery bow of, a bow handle having opposite end bow limb receiving sockets tapered inwardly from their outer ends with the rear wall of each socket at its outer end portion inclined rearwardly and outwardly to form a wedge engaging seat, upper and lower bow limbs having their inner ends tapered to fit into said tapered handle sockets, each bow limb being provided at the rear side of its inner end with a wedge member having its rear wall inclined upwardly and rearwardly and adapted to engage the seat formed by the 20 outwardly and rearwardly inclined rear wall of a limb receiving socket of the bow handle, said upper and lower bow limbs being mounted in assembled relation with the bow handle with the tapered inner ends of the limbs inserted in said 25 opposite end handle sockets, respectively, and a bow string connected between the opposite outer ends of said bow limbs, said bow string when drawn rearwardly to bend the limbs forcing said wedge members into engagement with said inclined walls to thereby further force the tapered inner ends of the limbs into said sockets.

7. The combination in an archery bow of, a bow handle having opposite end bow receiving sockets therein, a wall of each socket being inclined upwardly and outwardly, upper and lower bow limbs having their inner ends outwardly tapered to fit into said handle sockets, said upper and lower bow limbs being mounted in assembled relation with the bow handle with the tapered inner ends of the limbs in said opposite end sockets of the bow handle, a wedge member on each bow limb for cooperative engagement with the upwardly and outwardly inclined wall of the handle socket in which mounted, a bow string 50 adapted to be connected between the opposite outer ends of the bow limbs, and the bow string when drawn rearwardly bending the bow limbs and forcing said wedge members into cooperative 55 engagement with the inclined socket walls to thereby tend to further force and wedge the bow limbs into said sockets, respectively.
